[57] **CLAIM**

The ornamental design for bicycle brake unit, as shown and described.

DESCRIPTION

FIG. 1 is a front elevational view of bicycle brake arms of a bicycle brake unit showing my new design;

FIG. 2 is a rear elevational view of the bicycle brake arms showing my new design;

FIG. 3 is a first side elevational view of the bicycle brake arms showing my new design;

FIG. 4 is a second side elevational view of the bicycle brake arms showing my new design;

FIG. 5 is a bottom view of the bicycle brake arms showing my new design;

FIG. 6 is a top view of the bicycle brake arms showing my new design; and,

FIG. 7 is a perspective view of the bicycle brake arms showing my new design.

The drawings show brake arms of a bicycle brake unit used with a bicycle in accordance with my new design.

The broken lines shown in FIGS. 1, 2, 5 and 6 are shown for illustrative purposes only and form no part of the claimed design.
